(57) **CLAIM**

The ornamental design for a compartment bottle with label, as shown and described.

DESCRIPTION

FIG. 1 is a front elevational view of the compartment bottle with label;

FIG. 2 is a left side elevation view thereof, the right side elevation view being a mirror image;

FIG. 3 is a rear elevational view thereof; and,

FIG. 4 top plan view thereof.

The broken lines shown in the drawings are for environmental purposes only and form no part of the claimed design.
